SNUB TERMINAL CONNECTOR

Andrew Joseph Paucek, Flushing, N. Y., assignor
to Burndy Engineering Company, Inc., a corpora-
tion of New York

Application September 26, 1942, Serial No. 459,742

2 Claims. (Cl. 173—269)

My invention relates to electrical connectors.

The primary object of my invention is to provide an electrical connector for attaching a wire thereto, wherein the pull-out value for the wire from the connector will be substantially equal to the breaking strength of the wire itself.

Other objects of my invention are to provide a connector wherein the wire may be snubbed thereto to give maximum pull-out values, to provide electrical contact with the wire separable from the mechanical holding means; to provide a connection which will accomplish the foregoing objects with minimum deformation of the wire; to provide a connector body adapted to be compressed about the wire; to provide a connector to which the wire may be snubbed with the minimum strain on the wire; and to provide a one-piece connector adapted to mass production methods.

I accomplish these and other objects and obtain my new results as will be apparent from the device described in the following specification, particularly pointed out in the claims, and illustrated in the accompanying drawing, in which:

Fig. 1 is a plan view of my connector.

Fig. 2 is an end view thereof.

Fig. 3 is a front view of the same.

Fig. 4 is a sectional view taken along line 4—4 of Fig. 5.

Fig. 5 is a front view of my connector attached to a wire.

Fig. 6 is a perspective view of the same.

Fig. 7 is a perspective view of a modification, a part thereof broken away to indicate its cross-section.

Fig. 8 is a perspective view of a further modification, a part thereof broken away to indicate its cross-section.

In the drawing, the connector 10 may be provided with a terminal tongue 11, perforated at 12, and an extending connector body 13, which is H-shaped as shown in Fig. 3, providing two wall sections 14 and 15 separated by a web section 16, forming two longitudinal grooves 17 and 18, into which the wire is positioned.

In the connector neck 19 between the body 13 and tongue 11, an aperture 20 is formed through which the wire is inserted.

As shown in Figs. 2 and 3, the web section 16 is slightly tapered, which permits the end 22 of wire 21, shown in Fig. 3, to be looped through the aperture 20, and positioned in the grooves so as to occupy the minimum diameter when the connector body wall sections are compressed together as shown in Fig. 4.

Similarly, the outer edges 23 of the two wall sections may be tapered in the opposite direction of the grooves, so as to provide more metal where the wire is completely enclosed, giving the compressed outer surface of the connector body a cylindrical effect, as shown in Figs. 5 and 6.

The two grooves of the H-shaped body section may be placed in the same plane as the tongue section, thus eliminating the necessity for the aperture 20. This modification is shown in Fig. 7, wherein the tongue 30 is substantially an extension of the wall section 31 with wall section 32 separated by web section 33, forming grooves 34 and 35. The wire in grooves 34 and 35 is looped around the end portion 36 of the two grooves, which snubs the wire to the connector body, as the wall sections 31 and 32 are compressed about the wire therein.

In Fig. 8 there is illustrated a further modification in which the wire is produced about a circular rivet-shaped extension to the connector body. Here the tongue section 40 is an extension of the sheet metal plate 41 in which a rivet-like section 42 is produced by drifting the metal outwardly through the center of the plate. The flared ends 43 of the drifted metal produce a circumferential groove 44, into which the wire is positioned. A small cut-out 45 may be formed into one side of the flared end 43, for permitting the entrance and exit of the looped wire. The flared ends are turned in a rivet compressing machine which circumferentially compresses the wire.

I have thus provided a connector body that can be made by various methods, all forms providing means for snubbing the wire to the connector wall and compressing the wall about the wire to establish the maximum electrical contact.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained, and new results accomplished, as it is obvious that the particular embodiments herein shown and described are only some of the many that can be employed to attain these objects and accomplish these results.

What I claim and desire to secure by Letters Patent, is as follows:

I claim:

1. A connector for securing the end of a wire thereto, comprising a substantially rectangular body made of malleable metal and having grooved sections extending substantially about the perimeter thereof wherein the wire is positioned so as to form a loop; a terminal plate extending from the connector body transverse to the plane of the grooves having an aperture therein for the insertion of the wire therethrough and positioned adjacent the end of the grooved sections and between the rectangular body and the terminal plate, the portion of the connector body adjacent the grooves being compressible about the wire to secure the wire therein; said grooves converging at one end of the connector body, and diverging

at the other end of the connector body adjacent the aperture in the terminal plate.

2. A wire connection comprising in combination an H-shaped body the open portions of the H-shaped body constituting a pair of substantially longitudinal grooves extending through said body, a looped wire contained therein, one end of the H-shaped body being flat to form a terminal plate extending integrally from said body at the looped end of the wire, said wire tightly looped with the grooves in said body so as not to leave an open space between the wire and the body, the metal of said body compressed around the wires to form a cylindrical shape.
